UNITED STATES PATENT OFFICE.

JOHN CARLISLE McLAUGHLIN, OF JERSEY CITY, NEW JERSEY, ASSIGNOR TO UNDERWOOD TYPEWRITER COMPANY, OF NEW YORK, N. Y., A CORPORATION OF NEW JERSEY.

TYPE-WRITING MACHINE.

975,884.

Specification of Letters Patent. Patented Nov. 15, 1910.

Application filed November 9, 1909. Serial No. 527,013.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to the type bars and type bar supports of typewriting machines.

One of the objects of the invention is to provide a simple, durable and effective ball-bearing joint for the type bar, having provision for taking up looseness or wear, especially with a view to rendering the type bar joint very thin, so that the type bars may be assembled compactly together, as required in front strike writing machines.

Another object of the invention is to provide improved means for supporting a system of type bars upon a segment, particularly where the type bars are pivoted to individual hangers in the form of plates inserted in slots or sockets in the segment; and a special object being to render the hangers readily detachable from the segment and easily connectible thereto.

In the accompanying drawings, Figure 1 is a sectional side elevation of a portion of 30 an Underwood front strike writing machine, showing my present improvements. This view is taken on the line X—X of Fig. 3. Fig. 2 is an enlarged perspective view of the hub portion of the type bar and hanger upon which it is pivoted, and a fixed rod upon which the hanger is hooked. Fig. 3 is a part sectional front view of the segment and some of the type bars, one of the retaining plates for the type bar hangers being slipped up to release the hangers for detachment. This view is taken on the line Z—Z of Fig. 1. Fig. 4 is a section through the type bar joint taken at about the line Y—Y at Fig. 2. Fig. 5 is a part sectional front elevation of a portion of a segment to illustrate the curved rod which supports the type bars, one of the type bar hangers being shown hooked upon said rod. Fig. 6 is a fragmentary view corresponding to Fig. 1, but illustrating the method of detaching or attaching a hanger to the segment. Fig. 7 is a sectional fragmentary view to illustrate the construction of the slotted portion of the segment.

The type bars 1, usually in the form of

sheet metal plates, are pivotally supported upon a segment 2, to swing upwardly and rearwardly to print; being operated by keys 3 through the instrumentality of levers 4 and sub-levers 5. The type bars, in this instance, are articulated to plate-like hangers 6 secured in the segment.

Each hanger has upon one side a boss 7, which is coned at 8. The hub 9 of the type bar has a large eye 10, which is formed with an internal V-shaped ball-groove 11 containing a circle of bearing balls 12. The balls are held in place by a screw 13 threaded through the boss 7 of the hanger, and having a large thin head 14 coned on its inner edge to coöperate with the cone 8 of the hub and the groove 11 of the type bar eye to form a complete raceway for the circle of bearing balls; the head of the screw thus forming a retainer and bearing surface 7 for the balls. The screw may be tightened or loosened, as required, at any time, to bring the balls to a nice fit in the raceway; and may be secured by means of a nut 15, which occupies a recess 16 in the face of the hanger.

The structure, it will be observed, is very compact or thin, each of the elements 1 and 6 forming a thin plate, and these being placed very closely together, so that type bars may be assembled closely in the segment. Nothing projects from either the hanger or the type bar except the boss 7 of the hanger, and this projects into the eye of the type bar, so that the type bar and hanger may lie closely together. The boss on the hanger not only provides a cone for the balls to run on, but also affords sufficient thickness of metal for engagement by the threads of the screw 13, even though the hanger is recessed at 16 to receive the nut 15. Said recess may be of circular form and of less diameter than the boss 7, to leave sufficient metal for rigidity.

Each of the hangers 6 is formed at its inner end with a hook 17 to hook over a curved rod 18 fixed in the segment; the hangers fitting in radial slots or sockets 19 sunken in the front side or face of the segment 2. The curved supporting-rod 18 is placed in a circular groove 20 cut through the rear side of the segment and extending into the slotted portion thereof; the inner portion of the groove being enlarged or chambered at 21 to fit the rod 18, so that the latter cannot be displaced laterally, as it

cannot pass into the small portion of the groove 20. It will be understood that the rod may be inserted endwise into the chambered portion 21 of the groove.

5 After being hooked upon the rod 18, the hangers 6 are retained by a pair of keeper plates 22, the latter secured to the front of the segment by screws 23, which pass through slots 24 in the keeper plates; the 10 slots extending in such directions as to permit the plates to be slipped up to release the hangers 6, or slipped down to secure them.

Each hanger is formed with a shoulder 24^a, and offsets 25 upon the keeper plates 15 engage said shoulders and are pressed downwardly upon them, tending to turn the hangers backwardly around the rod 18, and hence to hold or press them firmly against their seats 26 in the segment, said seats consisting of the rear sides of the slots 19. The 20 screws 23 may be tightened to fasten the plates and hangers firmly to the segment.

To detach a type bar, it is only necessary to release the screws 23 holding one of the 25 keeper plates 22, and then to push said keeper plate upwardly as at Figs. 3 and 6, whereupon the hanger may be lifted a trifle and unhooked from the rod 18, and then pulled out from the socket. To attach a 30 type bar to the segment the operation is reversed. The ends of the keeper plates 22 may fit closely in guides 27 and 28, the latter answering for the adjoining ends of the two plates; said guides being in the form of 35 elbow plates secured upon the front of the segment and catching over the plates 22.

The number of the plates 22 may be varied, and other variations may be resorted to within the scope of the invention.

40 The hangers 6 may be employed in connection with other forms of joint between the hanger and the type bar; and the herein described type bar joint may be employed in 45 connection with other means for attaching the hanger to the framework of the writing machine.

Having thus described my invention, I claim:

1. A typewriting machine having in combination, a segment having radial slots, a series of type bar hangers in the form of plates seated in said slots and formed with hooks catching upon a rod mounted in said segment, and a plurality of independently 50 releasable retaining plates upon the segment for said hangers; each plate serving to retain a plurality of said hangers and having a plurality of screws to clamp it against the hangers, each plate slotted to permit it to 55 be moved off from the hangers to release them.

2. A typewriting machine having in combination, a segment having radial slots, a series of type bar hangers in the form of 60 plates seated in said slots and formed with

hooks catching upon a rod mounted in said segment, and a plurality of independently releasable retaining plates upon the segment for said hangers, said plates formed with offsets to engage shoulders formed upon the 70 hangers, and said segment formed with seats against which the hangers are pressed by the action of the offsets upon said shoulders.

3. A typewriting machine having in combination, a segment having radial slots 75 formed in its front side, the bottoms of said slots forming seats, a series of type-bar hangers in the form of plates inserted in said slots, a rod secured in said segment within the slots, said plates formed with 80 hooks to catch upon said rod, and a retaining plate secured upon the front side of the segment and releasably retaining said hangers, said plate formed with an offset to engage shoulders provided upon the hangers, 85 and thereby swing the hangers against said seats, and means to fasten the retaining plate to the segment.

4. A type-bar segment provided on one side with radial slots and having within said 90 slots a curved rod upon which the type bars are supported, said rod lying in a groove formed in the other side of the segment, the bottom of said groove enlarged to fit the rod, whereby the rod is confined against 95 lateral displacement, type bar hangers inserted in said slots and having hooks to catch over said rod, and means for releasably securing the hangers in the slots, said securing means including a plate fastened 100 upon the segment to engage a series of hangers and tending to turn the hangers about the rod and cause them to press against the bottoms of the slots.

5. A type-bar segment provided on one side with radial slots and having within 105 said slots a curved rod upon which the type bars are supported, said rod lying in a groove formed in the other side of the segment, the bottom of said groove enlarged 110 to fit the rod, whereby the rod is confined against lateral displacement, type bar hangers inserted in said slots and having hooks to catch over said rod, and means for releasably securing the hangers in the slots, 115 said securing means comprising a pair of plates secured upon the segment and engaging the hangers, said plates being secured by means of screws passing through slots in the plates and threaded into the segment, whereby upon releasing the screws the plates may be drawn up to release the hangers.

6. A type-bar segment provided on one side with radial slots and having within 120 said slots a curved rod upon which the type bars are supported, said rod lying in a groove formed in the other side of the segment, the bottom of said groove enlarged to fit the rod, whereby the rod is confined 125 against lateral displacement, type bar hang- 130

ers inserted in said slots and having hooks to catch over said rod, and means for releasably securing the hangers in the slots, said securing means comprising a pair of plates secured upon the segment and engaging the hangers, said plates being secured by means of screws passing through slots in the plates and threaded into the segment, whereby upon releasing the screws the plates may be drawn up to release the hangers, guides being provided upon said segment for the ends of said plates.

7. A typewriting machine having in combination, a segment having radial slots, a series of type bar hangers in the form of plates seated in said slots and formed with hooks catching upon a rod mounted in said segment, and a pair of independently releasable retaining plates upon the segment for said hangers, said plates having slots to engage securing devices projecting from the segment, whereby upon releasing said securing devices the plates may be drawn up to release the hangers, guides being provided upon said segment for the ends of said retaining plates.

8. In a typewriting machine, a type-bar segment having radiating slots formed with rear walls or bearings, a series of type-bar hangers in the form of plates seated in said slots, said segment provided with a rod, and said hangers having hooks to catch over said rod and also having shoulders adjacent to said hooks, and a single device common to said hangers and mounted on said segment to bear downwardly upon said shoulders to seat the hooks upon the rod and to cause the

hangers to turn around said rod and bear against the rear walls of the slots below said rod.

40

9. In a typewriting machine, a type-bar segment having radiating slots formed with rear walls or bearings, a series of type-bar hangers in the form of plates seated in said slots, said segment provided with a rod, and said hangers having hooks to catch over said rod and also having shoulders adjacent to said hooks, and a fastening plate common to said hangers and secured upon the segment to bear downwardly upon said shoulders to seat the hooks upon the rod and to cause the hangers to turn around said rod and bear against the rear walls of the slots below said rod.

45

10. In a typewriting machine, a type-bar segment having radiating slots formed with rear walls or bearings, a series of type-bar hangers in the form of plates seated in said slots, said segment provided with a rod, and

50

said hangers having hooks to catch over said rod and also having shoulders adjacent to said hooks, and a fastening plate common to said hangers and secured upon the segment to bear downwardly upon said shoulders to seat the hooks upon the rod and to cause the hangers to turn around said rod and bear against the rear walls of the slots below said rod.

55

11. In a typewriting machine, a type-bar segment having radiating slots formed with rear walls or bearings, a series of type-bar hangers in the form of plates seated in said slots, said segment provided with a rod, and said hangers having hooks to catch over said rod and also having shoulders adjacent to said hooks, and a fastening plate common to said hangers and secured upon the segment to bear downwardly upon said shoulders to seat the hooks upon the rod and to cause the hangers to turn around said rod and bear against the rear walls of the slots below said rod, said plate releasably mounted so that it may be shifted upwardly to release the hangers.
